JOSEPH FRASER HYSLOP, OF FALKIRK, SCOTLAND

CHECKER BRICKWORK CONSTRUCTION FOR REGENERATORS

Application filed March 30, 1932, Serial No. 602,057, and in Great Britain March 30, 1931.

This invention relates to improvements in checker brick-work for regenerators and aims to provide an improved construction giving an optimum relation of heating surface to 5 brick volume.

Essential to the invention are the formation or disposition of the checker bricks so that faces presented thereby and forming boundaries of vertical flues will be inclined 10 obliquely to closed walls between which the checker bricks extend, and the superimposition on each course of such checker bricks, in vertically spaced relation thereto, of a course of checker bricks similarly formed but 15 with their oblique faces oppositely inclined to those of the lower course, so that the planes of the oblique faces presented by such upper course intersect the planes of the oblique faces presented by the lower course, 20 whence there result vertical flues of approximately diamond or hexagonal section.

In practice, each checker brick may be formed with offset rectangular end portions joined by an oblique portion, in which event, 25 the checker bricks are supported at the ends by bricks of inverted T-shape; the rectangular ends of the checker bricks forming with the T-shaped bricks closed walls.

The checker bricks may be formed with 30 apertures, corrugations, grooves or the like to increase the effective surface and flue area.

In the accompanying drawing Fig. 1 is an elevation and Fig. 2 a plan of a checker brick-work construction according to the invention.

As shown in the drawing, the checker bricks 1 are so formed and disposed that the faces 2 presented thereby and forming boundaries of vertical flues 3 are inclined obliquely 40 to closed walls 4 between which the checker bricks extend. Superimposed on each course of such checker bricks, in vertically spaced relation thereto, is a course of checker bricks similarly formed but with their oblique faces oppositely inclined to those of the lower course, so that the planes of the oblique faces presented by such upper course intersect the planes of the oblique faces presented by the lower course, as seen clearly in 45 plan in Fig. 2. The vertical flues 3 are thus 50

of approximately diamond section or hexagonal section. It will be understood that the dimensions of the flues will be fixed in dependence on the type of furnace to which the invention is applied. 55

The inclined faces of the checker bricks may be continuous or may be stepped as shown at 1^a in Fig. 2.

As shown in Fig. 2 each checker brick 1 is formed with off-set rectangular end portions joined by an oblique portion, the bricks 5 supporting the checker bricks 1 being of inverted T-shape so that the rectangular ends of the checker bricks form with the T-shaped bricks 5 the closed walls 4 as shown 60 in Fig. 1. 65

What I claim is:—

1. Checker brick-work for regenerators comprising closed parallel walls including 70 staggered courses of supporting bricks of inverted T-shape, and superposed vertically spaced courses of checker bricks extending between said walls and formed with rectangular end portions filling the gaps left by said supporting bricks, said checker bricks presenting lateral faces disposed in vertical planes inclined obliquely to said closed walls and forming boundaries of vertical flues, the checker bricks of alternate courses having 75 oblique faces oppositely inclined to those of the other courses, whereby to afford vertical flues of approximately diamond section in plan. 80

2. Checker brick-work as claimed in claim 1 in which the inclined faces of the checker 85 bricks are stepped.

In testimony whereof I have signed my name to this specification.

JOSEPH FRASER HYSLOP.
